UNITED STATES PATENT OFFICE

161,062

BOX

Ted R. Stacey, Chicago, Ill., assignor to Tote-brush, Incorporated, Chicago, Ill., a corporation of Illinois

Application October 7, 1949, Serial No. 5,344

Term of patent 7 years

(Cl. D58—12)

To all whom it may concern:

Be it known that I, Ted R. Stacey, a citizen of the United States, residing at Chicago, in the county of Cook and State of Illinois, have invented a new, original, and ornamental Design for Box, of which the following is a specification, reference being had to the accompanying drawing, forming a part thereof, in which:

Fig. 1 is a top plan view of a box, showing my new design;

Fig. 2 is a front elevational view thereof;

Fig. 3 is a rear elevational view thereof; and

Fig. 4 is an end elevational view.

I claim:

The ornamental design for a box, substantially as shown.

TED R. STACEY.
